(57) **CLAIM**

The ornamental design for a double-handle pourable product container, as shown and described.

DESCRIPTION

FIG. 1 is a top perspective view of a double-handle pourable product container, embodying our new design;

FIG. 2 is a bottom perspective view thereof;

FIG. 3 is a top perspective view thereof, rotated 90 degrees to the left from FIG. 1;

FIG. 4 is a bottom perspective view thereof, in the position disclosed in FIG. 3;

FIG. 5 is a side elevation view thereof, showing the right side of the position shown in FIG. 1;

FIG. 6 is a side elevation view thereof, rotated 90 degrees to the left from FIG. 5;

FIG. 7 is a side elevation view thereof, rotated 90 degrees to the left from FIG. 6;

FIG. 8 is a side elevation view thereof, rotated 90 degrees to the left from FIG. 7;

FIG. 9 is a top plan view thereof; and,

FIG. 10 is a bottom plan view thereof.
